INFLATABLE BOAT

Fred F. Patten, Woonsocket, R. I., assignor to
 United States Rubber Company, New York,
 N. Y., a corporation of New Jersey

Application July 23, 1943, Serial No. 495,819

7 Claims. (CL 9—2)

This invention relates to improved collapsible boats and particularly to such boats having inflatable keels secured to the bottom of the boat.

Heretofore inflatable boats have been provided with keels constructed of fabric reinforced with rigid materials, such as struts of wood encased in pockets in the fabric. Keels of such prior construction do not provide the desired rigidity to the bottom of the boat because the reinforcing materials were made in sections and hinged together so that the keel could be folded. Furthermore, the rigid struts used in combination with the canvas presents a problem in collapsing and folding the boats into small packages, which may result in the tearing of the fabric and increasing the size of the folded boat.

The inflatable boat embodying the present invention is provided with an inflatable flexible keel, which is attached to the bottom of the boat. When the keel is deflated, it occupies a smaller space and is lighter than prior keels of the same effective size constructed of rigid materials. These advantageous characteristics facilitate the storage and transportation of the boat when it is out of the water. When the keel is inflated and is in the water, the inflated keel stiffens the boat, and thereby makes the boat easier to maneuver due to the decrease of the flow-resistance of the water against it and of any side slip of which there is a tendency to the latter when a sail and/or rudder is used. The inflatable keel also increases the buoyancy of the boat.

The foregoing and other objects of this invention will be more clearly understood by referring to the following description and accompanying drawing, in which:

Fig. 1 is a plan view of the boat embodying this invention;

Fig. 2 is a longitudinal side view of the boat shown in Fig. 1;

Fig. 3 is an enlarged cross-sectional view of the boat taken along line 3—3 of Fig. 1; and

Fig. 4 is an enlarged part of the view shown in Fig. 3.

Except as otherwise mentioned, the boat 10 illustrated in the drawings is made of flexible air impervious material, such as rubber or other air impervious synthetic coatings on canvas, and the parts are adhered together by the usual practice. The boat 10 is provided with a buoyant periphery 11 comprising one or more inflatable tubular chambers 12 enclosed in walls or tubes 13. A bottom 14 is secured to the buoyant periphery 11 by cementing the bottom thereto in the usual manner.

As shown in the drawing, a tapering inflatable keel 15 is secured to the bottom 14 of the boat 10. The keel 15 comprises an inflatable tube 16 which extends from the stern of the periphery 11 to the bow, and is cemented to the bottom 14 of the boat along its longitudinal center line 17 (Fig. 1). The union between the bottom 14 and the tube 16 is reinforced by pairs of fabric hinges 18 extending longitudinally along each side of the tube 16 and having their wings 19 and 20, respectively, cemented to the bottom 14 and the tube 16. Rigidity is imparted to the inflatable tube 16 and the union between the tube 16 and the bottom 14 is further reinforced by a longitudinally extending fabric side stay 21. The stay 21 embraces and is cemented to the tube 16, and has its longitudinal edges 22 cemented to the bottom 14 of the boat. The union of the edges 22 with the bottom 14 is further reinforced by fabric hinges 23 having their wings cemented respectively to the bottom 14 and the stay 21.

Before applying the side stay 21 to the tube 16 a heavy longitudinal strip of fabric 24 is cemented in a longitudinal fold 25 in the side stay. The side stay 21 is then cemented to the tube 16 so that the fold 25 extends along the bottom of the tube 16 and forms a longitudinal fin 26 extending along the bottom of the keel, as shown in Fig. 2. The side stay 21 is provided with vent openings 27 on each side of the tube 16 adjacent to the bottom 14 so as to vent the spaces 28 between the tube and the stay. The purpose of venting this space is to prevent air from being trapped in the spaces 28, so that the stay and the tube may be folded compactly. The vent openings 27 also admit water to the spaces 28, which acts as a ballast.

Means is provided for inflating the tube 16 through a valve 29 which extends through the bottom 14 of the boat and into the interior of the keel tube 16. The valve is constructed so that the usual hand pump or CO₂ bottle may be attached thereto for the purpose of inflating the tube through the bottom 14 of the boat 10.

The remaining portion of the boat 10 may be of the usual construction, wherein the peripheral tube or tubes 13 are made of fabric coated with natural rubber or other synthetic air impervious coating materials, and may be inflated through one or more valves similar to the valve 29. The boat is provided with an anchorage 30 in its bow 31 for securing a wooden mast 32 therein, to which a sail is adapted to be attached. The anchorage 30 comprises an upper fabric bracket 33 and a lower socket 34, cemented respectively

to the peripheral tube 13 and the bottom 14 of the boat. A number of anchoring tabs 35 is cemented to the peripheral tube 13 for the purpose of bracing the sail mast 22 with guy ropes (not shown) secured to the mast 22 and the tabs 35. The usual oar locks 36 and rudder holder 37 are anchored to the tubes 13. The boat is also provided with inflatable canvas seats 38 which are anchored to the peripheral tubes 13 at each end.

The preferred form of this invention has been described more or less in detail herein. It will be understood that the details may be changed without departing from the spirit of the invention and the scope of the appended claims.

Having thus described my invention, what I claim and desire to protect by Letters Patent is:

1. An inflatable boat having a flat canvas bottom, a keel secured to the outside of said bottom, said keel comprising an inflatable fabric tube having its ends tapering from its intermediate portion and merging into the contour of the bottom portion of the boat at the ends thereof.

2. An inflatable canvas boat comprising an inflatable periphery, a flexible bottom secured to the inflatable periphery, an inflatable keel secured to the outside of said bottom, and means extending through said bottom and into said keel for inflating same.

3. An inflatable boat comprising an inflatable periphery, a flexible bottom secured to said periphery, an inflatable fabric keel including an inflatable tube extending longitudinally of said bottom and cemented thereto, a side stay embracing and cemented to said tube, and the edges of said side stay being secured to said bottom on each side of said tube.

4. An inflatable boat comprising an inflatable periphery, a flexible bottom secured to said periphery, an inflatable fabric keel comprising an

inflatable fabric tube extending longitudinally of said bottom and cemented thereto, fabric hinges extending along each side of said tube and having one wing of each hinge cemented to said bottom and the other wing cemented to said tube, a side stay embracing and cemented to said tube, and the edges of said side stay being cemented to said bottom on each side of said tube.

5. An inflatable boat comprising a buoyant periphery, a flexible bottom secured to said periphery, an inflatable fabric keel secured to said bottom, said keel being reinforced by a longitudinal side stay embracing said keel and having its edges secured to said bottom on each side of said keel, and a fin extending along the bottom of said keel.

6. An inflatable collapsible boat comprising a buoyant periphery, a flexible bottom secured to said periphery, a keel including an inflatable tube secured to said bottom, said tube being reinforced by a side stay embracing said tube and having its edges secured to said bottom, a fin extending along the bottom of said tube and said fin comprising a longitudinal fold in said side stay.

7. An inflatable boat having a buoyant periphery, a flexible bottom secured to said periphery, an inflatable keel extending longitudinally along the central portion of said bottom, said keel comprising an inflatable fabric tube secured to said bottom, a side stay for reinforcing said tube, said side stay being cemented to said tube and having its longitudinal edges cemented to the bottom of said boat on each side of said tube, and said side stay having openings formed therein adjacent to said bottom so as to vent the space between said side stay and said tube adjacent to said bottom.
